ASH TRAY

Robert Wood, Red Bank, N. J.

Application July 16, 1952, Serial No. 20,623

Term of patent 7 years

(Cl. D85—2)

To all whom it may concern:

Be it known that I, Robert Wood, a citizen of the United States, residing at Red Bank, State of New Jersey, have invented a new, original, and ornamental Design for an Ash Tray, of which the following is a specification, reference being had to the accompanying drawing, forming a part hereof.

Fig. 1 is a perspective view of an ash tray, showing my new design, and

Fig. 2 is a cross-sectional view thereof, taken on line 2—2 of Fig. 1.

The characteristic features of my new design reside in the portions shown in full lines.

I claim:

The ornamental design for an ash tray, as shown and described.

ROBERT WOOD.
